SMOKER'S ARTICLE

Jens R. Schultz, Honolulu, Territory of Hawaii

Application June 10, 1943, Serial No. 490,323

1 Claim. (Cl. 131—209)

This invention relates to an article for smokers and is applicable to tobacco pipes and cigar and cigarette holders.

It is particularly aimed to provide a construction which utilizes a spiral passage or channel for the smoke, and is particularly aimed to provide one which will expose the maximum amount of smoke to a cooling influence, without increasing the normal effort of smoking, even when partially clogged with tar deposits, generally affording a milder, cooler smoke than at present is attainable, and with less effect on sensitive stomachs.

In addition, it is aimed to provide a structure which readily may be disassembled and cleaned.

The more specific objects and advantages will become apparent from a consideration of the description following taken in connection with accompanying drawing illustrating an operative embodiment.

In said drawing:

Figure 1 is a plan view of a tobacco pipe embodying my invention;

Figure 2 is a vertical longitudinal sectional view taken on the line 2—2 of Figure 1;

Figure 3 is a cross-sectional view taken on the plane of line 3—3 of Figure 2; and

Figure 4 is an elevation of the stem detached.

Referring specifically to the drawing wherein like reference characters designate like or similar parts, 10 designates a tobacco pipe bowl which may be made of briarwood or any other suitable material. This bowl is to be taken as representative since it may be a bowl, a cigarette holder, a cigar holder, or the like. This specific element 10 has a well at 11 in which the tobacco is disposed and ignited, and from which the smoke is withdrawn through a passage or channel 12 which preferably has a vertical portion 13 in communication with the well 11 centrally of its base.

Separable from the element 10 is a stem 14, a mouthpiece 15, also separable from the stem, and the stem and portions of the element 10 and mouthpiece 15 are surrounded and detachably engaged with a sleeve or shell 16.

Stem 14 may be made of any suitable material, preferably in one piece, as, for instance, from a suitable plastic, hard rubber, metal, or the like. At one end stem 14 extends slidably and removably into a socket or recess 17 of the element or bowl 10, abutting the same at the beveled end 18 and has an annular flange at 19 and a tapered portion 20. Stem 14 has a passage at 21 communicating with the passage 12 and having

branches 22 which deliver the smoke peripherally of the stem and into the interior of the shell 16, passing around the periphery of the stem in a spiral passage 23, defined by a spiral rib or flight 24 in intimate contact with the bore wall of the shell or sleeve 16.

Shell 16 preferably is of metal such as aluminum or an aluminum alloy in order rapidly to dissipate the heat from and to cool the smoke as it traverses the spiral passage. The rib 24 and passage 23 are so proportioned, the latter being relatively wide and the former relatively narrow, that maximum cooling of the smoke is attained.

The smoke emerging at the end of the passage 15 23 will enter a central longitudinal chamber 26 of the stem and then enter a tube 27 whose bore 28 communicates with the bore or passage 29 of the mouthpiece. Tube 27 may be made integral with the mouthpiece 15 or separate therefrom, as desired, and the tube and mouthpiece may be made of any suitable material, for instance, plastic, hard rubber, or any equivalent.

It will be noted that the shell 16 is separably connected to the bowl 10 or equivalent by a tapered sliding fit or equivalent joint at 30. Also, mouthpiece 15 is detachably applicable to the other end of the shell 16 as by a tapered sliding fit at 31. The inner end of mouthpiece 15 preferably does not contact the adjacent end of the stem 14 and hence a passage is provided whereby the smoke from the spiral passage 23 may enter the chamber 26.

To facilitate manipulation of the shell and mouthpiece in disassembling and assembling them, for cleaning and adjustment of the pipe or other smokers' article, the shell 16 is preferably enlarged and exteriorly at a multiplicity of ribs or the like 32, such ribs at the particular point shown functioning also in the dissipation of heat. Mouthpiece 15 preferably has an enlargement at 33 of any desired external configuration, to facilitate gripping and manipulation of it.

Various changes may be resorted to provided that they fall within the spirit and scope of the invention.

I claim as my invention:

A smoker's pipe comprising a bowl having a lateral shank, said bowl and shank having a passageway therethrough, the outer portion of the shank being internally and externally tapered, a shell having its opposite ends internally tapered, one end of the shell being wedgedly disposed over the tapered end of the shank, a hollow stem disposed in the shell and provided with an exten-

sion in one end thereof protruding into the passageway of the shank and having a tapered portion for wedged engagement in the shank, said stem being provided with a spiral rib on its periphery for snug engagement with the inside of the shell and to define a spiral passageway extending substantially from one end interior point to the other of the shell, a mouthpiece having a tapered inner end for wedged engagement in the remaining end of the shell, said mouthpiece having a passageway and a tube projecting from the mouthpiece and in alignment with the passage-

way thereof, said stem being hollow, closed at one end and open at its opposite end, the closed end of the stem being formed with a transverse port communicating through the extension with the passageway of the bowl and shank, said transverse port being in communication with the spiral passageway, said tube on the mouthpiece projecting into the open end portion of the stem, said stem at its open end terminating in spaced relation with respect to the adjacent end of the mouthpiece.
